UNITED STATES PATENT OFFICE.

JEREMIAH HORAN, OF WASHINGTON, DISTRICT OF COLUMBIA.

BUTTON.

SPECIFICATION forming part of Letters Patent No. 779,283, dated January 3, 1905.

Application filed June 25, 1904. Serial No. 214,148.

To all whom it may concern:

Be it known that I, JEREMIAH HORAN, a citizen of the United States, residing at Washington, in the District of Columbia, have invented new and useful Improvements in Buttons, of which the following is a specification.

This invention relates to improvements in collar, sleeve, or stud buttons, and the object is to provide a two-part button of simple construction the members of which may be readily and conveniently attached to or detached from each other for insertion in or removal from a garment and which when in contact with each other will not become accidentally disconnected.

With the above object in view the invention consists in the novel features of construction hereinafter fully described, particularly pointed out in the claims, and clearly illustrated by the accompanying drawings, in which—

Figure 1 is a side elevation of a button constructed in accordance with my invention. Fig. 2 is a sectional view through the base member and tubular shank carried thereby, showing the head member attached to the base member; Fig. 3, a side elevation of the head and spring-stem carried thereby, and Fig. 4 a view showing the swivel connection between the head and spring-stem.

Referring now more particularly to the drawings, 1 designates the base member, consisting of a base 2, of celluloid or other preferred material, having a central opening in which a tubular shank 3 is secured, and formed in its outer face with a concaved recess 4 in line with the shank. The shank is formed with a shoulder 5 at the inner face of the base or disk 2, and its end is turned back to form a shoulder 6, fitting into a depression in the base, thus securing the shank firmly to the disk or base. Said shank is formed tapering inside from end to end, the smaller diameter being at the inner or disk end of the shank.

45 At the outer end of the shank an exterior shoulder 7 is formed.

8 designates the head member, which consists of a stem 9, split to form spring members 10, upon the exterior of each of which, at one end of the stem, a shoulder or lug 11 is formed

by preferably turning down the material of which the stem is constructed. At the opposite end of the stem a setting 12 of any approved form is revolubly attached, said stem having a reduced portion 13 to fit in a central opening formed in the head, the end of the stem being headed, as at 14, which head 14 fits in a countersink formed in the setting or button-head 12.

In operation to connect the two members of the button the stem is inserted in the shank and moved inwardly therein, the inclined or tapered interior wall of the latter causing the spring members to be contracted or compressed until they pass beyond the inner end of the shank, when they again expand, the locking-lugs 11 engaging the end of the shank and holding the base and head members together. By providing a tapered or inclined inner wall for the shank, extending from end to end thereof, the spring members of the stem are gradually contracted, so that the inward movement of the stem may be easily and readily effected, and the spring members are not subjected to a sudden compression or contraction, as would be the case were a shoulder or projection provided simply at the inner end of the shank for effecting the result. The projecting shoulder 7 at the outer end of the shank serves to prevent the straddling of the shank by the spring members of the stem when the latter is inserted in the shank, the shoulder being of greater width than the space between the spring members. Thus by preventing the straddling of the outer end of the shank by the spring members the user is saved annoyance and the liability of bending or breaking of the spring members obviated. By forming the locking lugs or projections upon the exterior of the stem by reducing the diameter of the latter instead of forming lugs by compressing the metal of the stem a much stronger structure is provided. Also by swiveling the head or setting 12 to the stem it may rotate thereon, and should it catch in anything this rotation will prevent the disconnection of the two members of the button.

Having thus fully described my invention, what I claim as new, and desire to secure by Letters Patent of the United States, is—

1. A two-part button or stud comprising a base member, consisting of a base and a tubular shank having its interior wall tapered from end to end thereof with its smallest diameter 5 at its inner end, and a head member consisting of a head and a stem split to form two portions adapted to be inserted in said shank at the outer end thereof and to engage over the inner end of the shank.
- 10 2. A two-part button or stud comprising a base member, consisting of a base and a tubular shank having its inner wall tapered from end to end thereof having its smallest diam-

eter at the inner end, and a head member consisting of a head and stem split to form spring 15 portions adapted to be inserted in said shank from the outer end thereof and reduced upon its exterior to form projections at the outer ends of the split portions to engage over the inner end of the shank.

20 In testimony whereof I affix my signature in the presence of two witnesses.

JEREMIAH HORAN.
